UNITED STATES PATENT OFFICE.

FERDINAND W. NITARDY AND WILLIAM FANKHAUSER, OF BROOKLYN, AND FRANK ZACHMANN, OF JAMAICA, NEW YORK, ASSIGNORS TO E. R. SQUIBB & SONS, OF NEW YORK, N. Y., A CORPORATION OF NEW YORK.

DESIGN FOR A BOTTLE.

Application filed July 3, 1924. Serial No. 10,049. Term of patent 14 years.

To all whom it may concern:

Be it known that we, FERDINAND W. NITARDY, residing at and whose post-office address is 29 Monroe Place, Brooklyn, county of Kings, and State of New York, WILLIAM FANKHAUSER, residing at and whose post-office address is 734 Ocean Avenue, Brooklyn, county of Kings, and State of New York, and FRANK ZACHMANN, residing at and whose post-office address is 8621 143rd Street, Jamaica, county of Queens, and State of New York, citizens of the United States, have invented a new, original, and ornamental Design for Bottles, of which the following is a specification, reference being had to the accompanying drawing, forming part thereof.

We claim:

The ornamental design for a bottle, as shown.

FERDINAND W. NITARDY.
WM. FANKHAUSER.
FRANK ZACHMANN.
